MEANS FOR SECURING BARREL HEADS.

Application filed May 10, 1927. Serial No. 190,313.

This invention relates to the class of barrels, and has especial reference to the means for securing heads to the barrel body.

Some of the objects of the present invention are: to provide an improved means for permanently or removably securing a head to a barrel end; to provide a fluid-proof joint between the head and the barrel end; to provide means of the indicated character capable of withstanding extremely rough handling and comparatively great pressure externally or internally exerted thereon or applied thereto.

The nature of the invention and its distinguishing features and advantages will appear when the following specification is read in connection with the accompanying drawings, in which—

Figure 1 is a sectional elevation of a barrel end and the means employed for securing a head thereon;

Figure 2 is a plan view with parts broken away to illustrate more clearly certain features of the invention;

Figure 3 is an enlarged sectional view taken on the line 3—3 of Figure 1;

Figure 4 is a perspective view of the bevelled ring forming a part of the securing means; and

Figure 5 is a perspective view of one of the wedge members.

The present invention contemplates the securing of heads to barrels of the kind used for containing acids and the like, and for the production of a fluid-proof joint between the contiguous portions of the heads and the barrel ends, respectively, to prevent leakage, and also that the joints will be capable of withstanding extremely hard shocks and any comparatively great pressure whether externally or internally exerted thereon.

Referring now more particularly to the several views of the drawing, it will be apparent that there has been shown a barrel end 10, a head 11, and means 12 for securing the head 11 to the barrel end 10. The barrel end 10 has a bead 13. The head 11 consists of a crown 14 and a rim 15 having a flange 16. The barrel parts are of metal and are usually lined with rubber so as to effectively retain the acid contained therein.

The means 12 for securing the head 11 to the barrel end 10 comprises a ring 17, a plurality of wedge members 18, and a plurality of ring forming channel members 19. The ring 17 is bevelled as at 20. The said ring 17

is arranged on and surrounds the barrel end 10 in contact therewith. The bead 13 prevents the ring from slipping down or from moving beyond a certain point. After the ring 17 is in place the barrel end 10 has formed thereon a flange 21 contiguous to which the ring 17 will be disposed. The wedge members are adapted to co-act with the bevelled edge 20 of the ring 17, each of said members 18 being bevelled as at 22 for this purpose. Each wedge member 18 has a groove which accommodates a portion of the bead 13 and the barrel end 10 when the member 18 is in place. Each of the members 18 will be of metal and will be flexible. In the present instance two members 18 are employed, each being semi-circular, and it will therefore be understood that when the two members 18 are brought together they will form a ring. Members 19, each being in the form of a channel, will consist of a web 24 and flanges 25 and 26.

In order to secure the head 11 in place the parts are assembled as follows: The ring 17 will be put in place in the manner explained hereinabove, a suitable gasket 27 will be laid on the flange 21 of the barrel end 10. The head 11 will then be put in place, which will bring the rim 15 against the inside of a portion of the barrel end 10, and the flange 16 over the gasket 27. The wedge members 18 are then put in place in surrounding relationship with respect to the barrel end 10 in contact with the ring 17. The channel members 19 will then be associated in ring forming relationship which will bring the flanges 25, respectively, of the members 19 over the flange 16 of the head 11, the flanges 26, respectively; under the wedge members 18, and the webs 24, respectively, in contact with the wedge members 18.

A suitable clamping device is then brought into use to apply pressure on the channel members 19 to bring them together. This will cause pressure to be transferred by the webs 26 to the wedge members 18, setting up co-action between the bevelled portions 22, respectively, of these members and the bevelled portion 20 of the ring 17. This co-action of the bevelled portions respectively on the members 18 and ring 17 will cause impingement of the members 18 and the flanges 26, and at the same time will cause the flanges 25 to bear or press on the flange 16 of the head 11 and the ring 17 to bear against or press on the flange 21 of the barrel end 10.

end 10. As a consequence an effective and extremely tight joint will be established between the flange 16 of the head 11 and the flange 21, particularly so because of the 5 interposition of the gasket 27. The opposing ends of the channel members 19 will be connected together in any suitable manner. When it is desired to permanently secure the head, the opposing ends of the channel members 19 will be welded, as indicated at 28 in Figure 2 of the drawing. If it is desired 10 to removably secure the head 11, any suitable means may be provided for detachably connecting the channel members 19 together. 15 It is to be understood that the present disclosure is by way of example only and that certain minor changes in the construction of the parts may be made within the scope of the invention as expressed in the claims here- 20 unto appended.

Having thus described our invention, we claim:

1. The combination with a barrel end having a flange, of a head having a flange, a 25 ring contiguous the flange on the barrel end, a gasket between said flanges, and wedging means acting on said ring and flange on the head to press the flange on the head against the gasket and the gasket against the flange 30 on the barrel end, to produce a fluid proof joint between the head and the barrel end, said wedging means consisting of ring forming means, and flexible wedges, portions of said ring forming means respectively engaging the flange on said head and the wedges to set up the wedging action.
2. The combination with a barrel end having a flange, of a head having a flange, a 35 ring contiguous the flange on the barrel end, a gasket between said flanges, and wedging means acting on said ring and flange on the

head to press the flange on the head against the gasket and the gasket against the flange on the barrel end to produce a fluid proof joint between the head and the barrel end, 45 said wedging means consisting of a beveled portion on said ring, channel members connected together in ring formation, flexible arcuate wedges which coat with said beveled portion, and portions of said channel 50 members maintaining the co-action of said wedges and beveled portion.

3. The combination with a cylindrical container body having a circular flange at its open end, of a head fitting in the open end 55 of the body to close the same, said head having a circular flange overlying the flange on the body, a ring surrounding the body contiguous the flange on the body, wedges contiguous the ring, and semicircular channel 60 members arranged about said flanges, ring and wedges, said channel members being so constructed as to exert pressure on the wedges and the flange on the head to force the flanges into sealing relation.

4. The combination with a barrel end having a flange, of a head having a flange, a gasket between the flanges, a pair of semicircular wedges embracing the barrel end, a beveled member between the wedges and the flange on the barrel end, and semicircular channel members enclosing the flanges, gasket, beveled member and wedges, said channel members serving to exert pressure on the flange on the head and its wedges to 70 cause the flange on the head to press against the gasket and the gasket against the flange on the barrel end to produce a fluid tight joint between the head and the barrel end.
